AUTOMATIC SPRINKLER

Leroy M. Lewis, Rosemont, Pa.

Application November 23, 1946, Serial No. 711,979

1 Claim. (Cl. 169—38)

1

My present invention relates to an improvement in automatic sprinklers such as are commonly employed for automatically releasing a stream of water or a fire extinguishing liquid in a frangible container, whenever a certain predetermined temperature has been reached in the vicinity where such automatic sprinkler is located.

Specifically, my present invention is an improvement over the construction and relationship of parts shown in my prior patent, No. 2,125,510, patented August 2, 1938, wherein I disclosed one form of frangible vessel or bottle having a predetermined rupturing temperature. In my present application, I am improving this form of frangible vessel or bottle in a way to provide the most effective means for sealing the contents thereof from escape to the outside atmosphere.

Another important feature of my invention consists in the provision of a series of metal caps having markings thereon of gradually increasing temperatures for the purpose of applying the appropriate metal cap of the series to a frangible bottle having the corresponding predetermined rupturing temperature, as indicated by the marking.

Another feature or object of my invention is the use of a specific mounting for a frangible vessel or bottle comprising a link structure having fusible material which releases the suspended frangible bottle at a temperature lower than the predetermined temperature of rupture of such bottle.

A further object of my invention is the provision of a mounting device for a frangible vessel or bottle adapted to secure the frangible bottle in position so as to provide uniformity of pressure peripherally about the neck thereof adjacent the air space above the expansive material or liquid.

Another object of my invention is a novel form of closure means or cap for the frangible bottle by means of fusing a metal cap to the outer edge or rim of the neck of the bottle.

A further object of my invention is the provision of a variety of forms of metal closure caps adapted for use in frangible bottles under varying conditions, one form of such cap involving merely a disk-shape, a second form being adapted for suspending the bottle, and a third form of cap providing means of access to the trapped air at the sealed end of the bottle.

5 A specific object of my invention is the desirability and possibility of providing an accurate method of controlling automatic sprinklers by means of providing a frangible bottle of the desired pressure and temperature sensitiveness so as to meet a wide range of uses under varying conditions.

10 A general object of my present invention is to assemble the frangible bottle in position relative to the closure of the pipe fitting, thereby releasing water under pressure upon fracture of the bottle.

15 The invention consists in the novel construction and combination of the several parts, as will be hereinafter fully set forth and pointed out in the claim.

20 Other objects will appear and be better understood from the several embodiments of my invention which are set forth in the following detailed description.

25 Reference is now directed to the accompanying drawings forming a part of my specification, in which:

25 Figure 1 is a perspective view of one form of mounting device for an automatic sprinkler, comprising a large container or bulb, preferably spherical, containing carbon tetrachloride and which is adapted to fracture at a predetermined temperature.

30 Figure 2 is a perspective view of the metal cap for the frangible container or bulb of the device of Figure 1.

35 Figure 3 is a cross-section taken on the line 3—3 of Figure 2.

35 Figure 4 is a perspective view of a second form of mounting device for an automatic sprinkler, in which the frangible bottle or container acts as a part of the holding means for the closure or cover of the open end of a yoke member.

40 Figure 5 is a perspective view of one form of frangible bottle element suitable for the mounting device of Figure 4.

45 Figure 6 is a cross-section taken axially through a modified form of frangible bottle specifically adapted for the mounting device of Figure 4.

A preferred method of mounting a frangible bottle in position as a safety means for fire extinguishers comprises a vertically mounted bracket member having a pair of horizontal arms

8, 8 projecting from a vertical rod 7, supported in a wall bracket 10. Centrally positioned between the horizontal arms 8, 8 is a fusible link 5 having a relatively low melting point which is carefully selected to be lower than the predetermined temperature of rupture of the frangible bottle or container 1, so that such bottle will be released a short time before the critical temperature selected for the automatic sprinkler. The fusible link 5 is suspended from the upper arm 8 and is positioned between a pair of links 6, 6. Furthermore, the fusible link 5 carries the lowermost link 6 from which the frangible vessel or container 1 is suspended. Container 1 is preferably made spherical and relatively large for the purpose of carrying a suitable quantity of carbon tetrachloride, which upon fracture of the container 1 at the predetermined temperature will cause a release of such contents for the purpose of extinguishing the fire or heat effect producing the predetermined temperature.

The cap 2 of the container 1 is of general disk-like shape provided with an eyelet 3 for purpose of suspension, and the inner side of such cap member is fused at 4 to the outer edge or rim of the bottle neck, thereby providing an hermetical seal of the bottle contents. It is here noted that a portion of the outer side of the cap 2 is disk-like in shape providing a flat surface for receiving the temperature mark of 135° F., such being the critical temperature for the fracture of the frangible vessel or bottle 1 which is loosely suspended in the mounting of Figure 1, and positioned between the prongs of the fork or yoke 9 at the outer end of the lowermost horizontal arm 8.

The eyelet 3 on the cap 2 of the frangible bottle or container permits anyone in the vicinity of the fire to pick the bottle by hand away from the lowermost link 6 and throw it at the fire. The subsequent impact will break the bottle, the contents extinguishing the fire.

Referring now to the mounting device, shown in Figure 4, the automatic sprinkler therein is provided with a fitting, including a yoke member 20 which carries at one end a threaded plug 11, which is designed to be threaded into the extremity of a pipe (not illustrated). Such a pipe constitutes a source of water supply receiving water under pressure, and the plug 11 has a bore 12 which is closed by a valve seat member 36 of bronze material having a copper insert or gasket 37 to receive the bottom portion of the frangible bottle member 22. The valve seat member 36 has a copper facing or liner 38 on its closure side suitably shaped to seat upon an annular flange 21 concentric with the bore 12.

At the upper end of the yoke member 20, I provide a bridge member 23 bearing centrally against the metallic cap 35 of the frangible bottle 22. This bridge member is formed from bronze alloy or material and is provided with a small recess or depression 25, constructed to receive the pointed end 26 of a threaded adjusting stem 27. This stem 27 is carried by the yoke 20 and is provided with an operating member in the form of a hand wheel 28.

It is noted that the frangible bulb 22 is of substantially acorn formation, although the particular shape or size of such bulb or bottle is not the essence of my invention.

The frangible bulb or bottle 22 is provided with a wall structure 29 substantially uniform throughout, and has an open end at 30 which is defined by a neck 31. A desired quantity of some expan-

sive material susceptible to the influence of heat, and subsequent expansion, causing fracture of the bottle upon a predetermined temperature being reached, is placed in the bottle 22. Carbon tetrachloride is one material which has been found suitable for this use.

A stopper or cork is shown at 32 which may be placed downwardly in the neck 31 so as to build-up pressure in the air above the expansive material, in this instance being carbon tetrachloride and indicated at 33. After the cork or stopper 32 has been positioned, a cap member 35 of flat disk-like shape is positioned over the edge or rim of the neck 31. This cap member 35 is metallic and is fused directly to the edge or rim of the bottle in the same manner as is indicated at 4 in the modification of bottle, as presented in Figures 2 and 3.

This method of connecting the cap member 35 to the bottle 22 provides an unusually efficient and effective hermetic seal and is one of the essential features of my present invention. The temperature of 175° F., is one of the critical temperatures, especially adapted for automatic sprinklers, and such marking has been placed upon the metal cap 35 of Figure 5.

The specific type of bottle, shown in Figure 5, is especially adapted for use in the yoke member 20 of Figure 4 wherein the bridge member 23 is of inverted U-shape and is adapted to be adjusted vertically downward and axially about the outer edge of the metallic cap member 35, thereby producing uniformity of pressure about the periphery of the neck 31 of the frangible bottle 22.

A modified type of metal cap is disclosed in Figure 6 of the drawing and comprises a cap member 44 having a central tubular neck 45, the inner side of such cap being fused to the outer edge or rim of the bottle neck at 4; in the same manner as has been embodied in the modification of cap, shown in Figures 2 and 3. The tubular neck 45 of the cap 44 is externally threaded and the bore thereof is covered by an internally threaded cap member 46 adjustable thereon. This construction provides for adjusting the pressure of the air or gas in the frangible bottle 22, as well as permitting the introduction of other or additional gaseous material to the bottle.

After the frangible bottle 22, of Figure 4, has been properly assembled as an automatic sprinkler, upon the predetermined temperature of 175° F. being reached in the vicinity of such bottle, rupture of the bottle will occur, and the water pressure will operate through the bore 12 of the yoke member 20, providing a stream of water for extinguishing the fire.

While several preferred embodiments of my invention are herein set forth, my invention is not to be limited to the exact construction illustrated and described, because various modifications of the details may be provided in putting the invention into practice within the purview of the appended claim.

What is claimed is:

In an automatic sprinkler head assembly including a yoke member, a threaded plug carried by said yoke member at one end thereof and having a bore extending therethrough, said plug being adapted to be connected to a source of supply of water under pressure, a cover member for said bore, said cover member having a face remote from said bore and which face is formed with a curved depression, a screw stem threaded in the other end of said yoke; and a bridge member en-

gaged by said stem; the improvement consisting of a fracturable glass bottle having a main body portion with a lower end curved to conform to said depression in which it is received and a reduced neck upstanding from said body portion, said neck having a bore communicating with the interior of said bottle, a cork within the bore in said neck and having an outer face spaced from the outer end of the bore in said neck, and a cap in the form of a flat metallic disc with its outer edge portion fused to the end of said neck to close the face thereon, said cap being engaged by said bridge member under pressure to maintain said cover member in position closing the bore in said plug.
